UNITED STATES PATENT OFFICE

EDWARD L. RIVET, OF CHICAGO, ILLINOIS

COMBINED ORNAMENT AND DISPENSER

Application filed February 15, 1929. Serial No. 340,258.

This invention relates to an article of manufacture providing means for emitting or dispensing an odoriferous commodity, the article being capable of being worn by a person as an article of jewelry or located in a room or any other desired place.

The invention has as its principal object the production of an article which provides an article of jewelry which will perform the dual function of a dispenser for perfume and adornment for the person.

The invention has as a further object the provision of a construction having the above characteristics, which is capable of being readily recharged with the perfume or odoriferous commodity and in which the part providing the container will be concealed from view by the part forming the ornament.

It is another object of the invention to provide a container for odoriferous commodities which will retain the commodity in a liquefied form and allow its consumption by evaporation and to construct the container of a material which is of a non-absorbent character and which will retain an amount of the commodity sufficient to suffice for a certain period.

The invention will be explained with reference to the accompanying drawing which illustrates various embodiments of the invention, it being therefore obvious that the invention is capable of further modification without departing from the spirit of the appended claims forming a part thereof.

In the drawing,

Fig. 1 is a central longitudinal section of a device embodying a construction whereby the various advantages may be accomplished.

Fig. 2 is a view showing the elements of Fig. 1 in a changed position.

Fig. 3 is a sectional view taken on the line 3-3 of Fig. 1.

The structure illustrated in Fig. 1 discloses a combination of elements which, when combined with each other, produce an article which serves the dual capacity of an adornment for the person and a dispenser of a perfume, thereby accomplishing the effect without necessitating the application of the per-

fume to the garment. This embodiment of the invention contemplates the combination of a necklace or means of attachment 10, the ornament 11, which forms a housing, a support 12 for the ornament, which support is attached to the necklace, and an element 13 which provides a container for the perfume. The opposite ends 14-14 of the necklace 10 are secured to one end of the support 12 and this support has an enlargement 15, provided at its opposite end, which acts as a stop to limit movement of the ornament and thus retains all of the elements of this structure in proper relation to each other when worn by the person. The support 12 forms a means to which the perfume or commodity container 13 may be attached or be supported. The ornament 11 is provided with the longitudinally extending bore 16, having the relatively large portion 17 and the reduced portion 18.

When this article is worn by the person, the ornament 11 assumes a position with respect to the other elements of the structure in which the end 19 of the ornament rests against the enlargement or stop 15, and since the diameter of the container substantially corresponds with the diameter of the portion 17 of the bore of the ornament, the ornament will be maintained against lateral movement relatively to the support 12 when the device is worn as an adornment to the person or suspended in a similar manner in a room, should it be desired to employ the device in this manner.

When it is desired to charge the commodity container 13, the ornament 11 is moved upwardly relatively to the support 12 and along the necklace 10, which will expose the container and allow it to be dipped into the perfume or other commodity, after which the ornament 11 is again brought to a position relatively to the container, in which it forms a housing for the container. It is evident that when the container is charged and arranged in the manner just referred to, that as the perfume evaporates it escapes through the opening 18 and between the end 19 of the bore and enlargement 15, and thus will accomplish the same result as direct application of the perfume to the garment.

The container for the commodity, as before stated, is of a non-absorbent character, which retains the commodity in its liquid form and prevents its escape in this form from the container. To this end the container 13 is formed of a sheet of wire mesh screen or fabric, which is wound around the shank of the support 12. This provides a plurality of minute cells in each of which a certain amount of liquid is retained until removed therefrom by evaporation.

From the foregoing description of the structure shown in Fig. 1, it is manifest that an article is produced which provides the dual function of an ornament and a dispenser in which the ornament may be moved relatively to the other elements of the device to thus expose the container for the commodity and allow its being immersed into the commodity to charge it with the commodity, after which said ornamental portion may again be arranged to enclose or conceal the commodity container.

It is further evident that the commodity container is of a non-absorbent character which will retain the commodity in liquid form and allow its being dispensed by evaporation.

Having thus described my invention what I claim and desire to cover by Letters Patent is:

1. In a device of the kind described, the combination of an element having an enlargement at one end, and a flexible member secured to the opposite end, a metallic porous member wound upon said element and providing a container, a member slidably mounted upon said flexible element and providing a housing for said porous member, said housing member being supported by said enlargement and being movable relatively to said element while in associated relation with said element to thereby arrange said element and member to expose said porous member with said element and member in associated relation with each other.

2. In a combined ornament and perfume dispenser, the combination of a flexible element having a container connected therewith, a tubular housing for said container slidably connected with said flexible element and container to expose and enclose said container, and means for limiting movement of said housing in one direction relatively to said container and flexible element.

3. In a combined ornament and perfume dispenser, the combination of a flexible element having a wire mesh providing a container associated with said flexible element for support by said flexible element, a tubular housing for said container slidably connected with said flexible element and container to expose and enclose said container, and means for limiting movement of said housing in

one direction relatively to said container and flexible element.

4. In a combined ornament and perfume dispenser, the combination of a container comprised of a member having a wire mesh wound thereon, a flexible element connected to one end of said member, a tubular element providing a housing for said container, said tubular element being slidably movable in opposite directions lengthwise of said flexible element and member into and out of functional relation with said container, and means for limiting movement of said housing in one direction relatively to said container.

5. In a combined ornament and perfume dispenser, the combination of a flexible element having a member associated therewith providing a container, an open ended member providing a housing for said container, said open ended member being slidably mounted upon said element, said element and member being movable endwise relatively to each other to arrange said member upon said element and relative to an end of said element to expose and enclose said container.

In witness whereof, I hereunto subscribe my name this 14th day of January A. D., 1929.

EDWARD L. RIVET.
